V. F. DAVIS,
HEATER FOR INCUBATORS,
APPLICATION FILED APR. 5, 1919.

Patented Aug. 3, 1920.

INVENTOR.
VERNER F. DAVIS

BY *Thomas L. Wilder*
ATTORNEY.

UNITED STATES PATENT OFFICE.

VERNER F. DAVIS, OF ORANGE, NEW JERSEY, ASSIGNOR TO PERCY D. PETERS, OF LITTLE FALLS, NEW YORK.

HEATER FOR INCUBATORS.

1,348,784.

Specification of Letters Patent. Patented Aug. 3, 1920.

Application filed April 5, 1919. Serial No. 287,780.

To all whom it may concern:

Be it known that I, VERNER F. DAVIS, a citizen of the United States, residing at Orange, in the county of Essex and State of New Jersey, have invented certain new and useful Improvements in Heaters for Incubators, of which the following is a specification, reference being had therein to the accompanying drawing.

10 My invention relates to a heater for incubators and I declare the following to be a full, clear, concise, and exact description thereof sufficient to enable anyone skilled in the art to which it appertains to make and 15 use the same reference being had to the accompanying drawings in which like reference characters refer to like parts throughout the specification.

The object of the invention is to provide a 20 suitable heater for incubators or brooders that will be of simple construction. The heater is equipped with draft doors and vents that respond quickly to any variation in temperature in the incubator or 25 brooder, whereby to keep the temperature therein at a normal degree.

To this end, the heater is provided with draft doors that are actuated by mechanism controlled by the temperature of the water 30 that passes through the pipes located within the interior of the incubator.

The object will be understood by referring to the drawings in which:

Figure 1 is an elevation of the heater, 35 showing the mechanism for actuating the draft doors;

Fig. 2 is a vertical section of a fragment of the heater, showing the check or coaling door in wide open position;

40 Fig. 3 is an enlarged perspective view of the check or coaling door and clevis, showing their relative positions;

Fig. 4 is an enlarged perspective view of the arm or clevis;

45 Fig. 5 is an enlarged perspective view of a buckle employed;

Fig. 6 is an enlarged perspective view of a throttle rod and throttle valve employed, showing the relative position of a cross pin 50 mounted in said throttle rod.

Referring more particularly to the drawings, the heater is represented by —1— and has a check or coaling door 2, which is provided with the arms 3—3, whereby it is 55 hinged upon trunnions or pivots carried

by the lugs 4—4 formed integral with the heater frame.

The door 2 is operated open and shut automatically, whereby to check or increase the draft of the fire in the heater —1— by 60 the lower end 5 of an arm or rock clevis 6. The clevis 6 is fulcrumed at 7 to the brackets 8—8 formed integral with the frame of the heater —1—. The opposite end of the clevis 6 is bifurcated and its ends 65 straddle the throttle rod 9 which carries a cross pin 10. The pin 10 is adapted to bear down on the bifurcated ends of the clevis 6 and rock said clevis 6 upon its fulcrum 7, whereby to cause it to open the check or 70 coaling door 2.

The upper end of the throttle rod 9 is screw mounted to the aperture 15 of a buckle 16 and locked by a nut 18. The buckle 16 being used to allow a certain amount of 75 longitudinal adjustment for the rod 9. The upper bifurcated ends 17—17 of the buckle 16 have alining holes, which form bearings for a pin or shaft carried by the end 35 of the lever 20. The lower end of the throttle rod 80 9 passes through an aperture in the throttle valve 11 which seats on the ring 12 formed in the top portion of the frame of the heater —1—. The aperture in the throttle valve 11 for the projection of the throttle rod 9 is sufficiently large to permit the rod 9 to 85 continue to operate downward after the valve 11 is seated if necessary. The adjustable lock nuts 14—14 are mounted upon the throttle rod 9 below the throttle valve 11, 90 whereby to elevate said valve 11 to aid in creating a draft when desired.

The lever 20 is fulcrumed at 21 to a bracket 22 fastened to the tank 25 which contains a float 26 that is connected to the lever 20 by a link 27. The link 27 is pivoted at 28 to said lever 20. The opposite end of the lever 20 from that to which the rod 9 is attached is threaded for mounting the adjustable weight 30, whereby the tilting of the lever 20 can be controlled to a very fine degree in order to respond more or less quickly to any change in temperature within the incubator. The lever 20 is formed with a bend or offset at 31 to clear the edge of the 100 tank 25 and thereby allow for the proper tilting of the lever 20.

The lever 20 is connected also to the lower draft door 32 of the heater —1— by a stiff wire 33 and a chain 34. The chain 34 being 110

used to localize the slack adjacent said lever 20. The door 32 is hinged at 35-35 to the frame of the heater —1.

The operation of the heater under normal draft conditions is such that when the temperature of the water is sufficient to heat the incubator to the proper degree its volume in the tank 25 will be expanded to such a point that the outer end 35 of the lever 20 will have been depressed to lower the rod 9 and seat the valve 11 upon its ring or seat 12, thereby checking the draft. The chain 34 and wire 33 will have been lowered simultaneously to close the draft door 32. Should the closing of the throttle valve 11 and the draft door 32 be insufficient to check the fire and the temperature of the water in the incubator still increase, the expansion of said water in the tank 25 due to such increased heat 20 will cause the float 26 to rise higher and tilt the lever 20 to a greater angle, whereby the rod 9 will descend still farther, thereby causing the pin 10 to make contact with the bifurcated ends of the arm or clevis 6. This 25 contact of the pin 10 with the arm 6 will rock the arm or clevis 6 upon its fulcrum 7, whereby the end 5 thereof will open the check or coaling door 2, so as to effect a lower temperature in the incubator to that of the desired degree. 30 On the other hand should the temperature of the water in the incubator become lower than the desired degree, the expansion of the water in the tank 25 will decrease to a smaller volume, thereby lowering the float 35 26 and elevating the end 35 of the lever 20. The elevation of the end 35 of the lever 20 will effect an elevation of the rod 9 which action will result first in closing the check or 40 coaling door 2. If the rod 9 still continues to rise under the influence of the decreased volume of the water in tank 26, the throttle valve 11 will be unseated and the draft door 32 be opened, the latter by means of its connection with the lever 20 through the chain 45 34 and wire 33. The unseating of the throt-

tle valve 11 and the opening of the door 32 will effect a draft as indicated by the arrows in Fig. 2, whereby to start up the fire in the heater.

Having thus described my invention what I claim as new and desire to secure by Letters Patent is:

1. In a heater for incubators, a draft door under the fire, a throttle valve over the fire, a check door between the fire and throttle valve, a float, a lever operatively governed by said float, a rod connecting the lever and throttle valve, a clevis fulcrumed to said heater, a pin carried by said rod, and adapted to actuate said check door, and a chain connecting said lever with the draft door under the fire, whereby to actuate said draft door.

2. In a heater for incubators, a draft door under the fire, and an adjustable throttle valve over the fire, a check door between the fire and throttle valve, a float, a lever operatively governed by said float, an adjustable rod connecting the lever and throttle valve, a clevis fulcrumed to said heater, a pin carried by said adjustable rod and adapted to actuate said check door, and a wire and chain connecting said lever with the draft door under the fire, whereby to actuate said draft door, to control the fire.

3. In a heater for incubators or brooders having a coal fire, a draft door under the fire, a throttle valve over the fire, a check door adapted for use as a coal feed door and located between the fire and the throttle valve, a float, a lever operatively governed by said float and so arranged as to open the check door when the draft door under the fire and the throttle valve are closed.

In testimony whereof I have affixed my signature.

VERNER F. DAVIS.
